LILBURN HOWARD VAN BRIGGLE, OF INDIANAPOLIS, INDIANA.

CARBURETER.

1,273,554.

Specification of Letters Patent. Patented July 23, 1918.

Application filed February 9, 1916. Serial No. 77,127.

To all whom it may concern:

Be it known that I, LILBURN HOWARD VAN BRIGGLE, a citizen of the United States, residing at Indianapolis, in the county of Marion and State of Indiana, have invented a new and useful Carbureter, of which the following is a specification.

It is the object of my invention to provide a carbureter which produces an intimate mixture of the fuel and air; which will produce an opening of the fuel control valve upon the opening of the throttle, with the movements of the throttle and the fuel control valve relatively adjustable; which can 10 cut off the supply of both primary and secondary air together for obtaining a rich mixture at starting, and by such cutting off, though preferably only at the last part thereof, produces an opening of the fuel 15 control valve to obtain a further enrichment of the mixture; in which the fuel control valve may be opened independently by either the opening of the throttle or the cutting off of the air supply; which produces 20 a swirling movement of the primary air, thereby finely atomizing the liquid fuel and preventing any loss thereof; and which may be adjusted to compensate for variations 25 in the number of cylinders and in the suction obtained in different engines.

The accompanying drawing illustrates my invention. Figure 1 is a partial elevation and partial vertical central section of a carbureter embodying my invention; Fig. 35 2 is a reduced section on the line 2—2 of Fig. 1; and Fig. 3 is a partial section on the line 3—3 of Figs. 1 and 2.

The main body 10 of the carbureter has a central dependent tube 11 which at its upper end opens into a horizontal passageway 12 at an intermediate point of the latter. This horizontal passageway at one side (the left) is provided with a downwardly opening, automatic secondary air valve 13, which is spring-pressed upward by a spring 14 and is opened downward by the engine suction in accordance with the demands and is controlled in its movements by an air dashpot 15; and at its other side (the right) is

turned upward and provided with a flange 50 16 for connection to the inlet manifold of the engine, and has a butterfly throttle 17 mounted on a shaft 18 and operated by a connecting rod 19 leading to any suitable control point.

A Venturi tube 20 depends into the central tube 11 and has a screw thread mounting 21 at the juncture of such central tube 11 with the horizontal passageway 12, so that the entrance from the central tube 11 60 to such horizontal passageway 12 must be through the Venturi tube. A fuel nozzle 22 discharges upwardly within the Venturi tube 20 at approximately the most contracted portion thereof, and receives its supply 65 of fuel through a passageway 23 communicating with a fuel bowl 24 surrounding the central stem 11 and having the fuel level therein controlled in the usual manner by a float valve 25. A needle valve 26 controls 70 the outlet of the fuel nozzle 22, and projects centrally downward across the horizontal passageway 12 and along the axis of the Venturi tube 20, its upper end extending 75 through a removable screw plug 27 and having an adjustable screw-thread mounting in one end of a lever 28 mounted on a pivot pin 29 on the main body 10. A spring 30 presses upward the other end of the lever 28, thus tending to seat the needle valve 26. A downward curved projection 31 from the spring-pressed end of the lever 28 carries 80 at its lower end a roller 32 which cooperates with a rigid arc-shaped cam 33 having at one end a pivotal mounting 34 on an arm 85 35 fixed on the shaft 18 and at its other being provided with an undercut radial slot 36 which receives a ball 37 on the end of a screw 38 mounted in an arm 39 also fixed on the shaft 18, the two arms 35 and 39 conveniently being extensions from a collar 90 mounted on the shaft 18 so that by adjusting such collar the two arms are adjusted together. By adjusting the screw 38 the outside convex surface of the rigid arc-shaped cam 33 may be made eccentric of the shaft 18 by any desired amount, so that when such shaft 18 is turned to vary the

sition of the throttle 17 the arc-shaped cam 33 moves the roller 32 and lever 28 against the spring 30 or allows them to be moved by the spring 30 to move the needle valve 26 upward or downward to vary the opening of the fuel nozzle, increasing such opening as the throttle is opened and vice versa.

The lower end of the Venturi tube 20 is spaced from the inner walls of the depending tube 11, and the depending tube 11 near its upper end communicates with a lateral primary air supply passage 40 which conveniently is curved downward at its intake end as illustrated. This primary air inlet passage is of larger transverse dimensions horizontally than vertically, and discharges into the central tube 11 at one side of the center thereof, as apparent from Figs. 2 and 3, and preferably slightly downward, as apparent from Fig. 1, so that the primary air is discharged from such supply passage 40 tangentially and slightly downwardly into the central tube 11 and so is caused to travel with a swirling motion in a descending helix around the outside of the Venturi tube 20, which swirling or helical motion continues as the air passes around the lower end of such Venturi tube and up through such tube and into the horizontal passageway 12. This swirling motion of the primary air picks up any fuel which drops to the bottom of the central tube 11, thus preventing any loss of fuel, and also breaks up into very fine-particles the fuel discharged by the fuel nozzle 22, and produces an intimate mixture of such fuel with both the primary air and the secondary air.

Mounted in the primary air intake passage 40 is a butterfly cut-off valve 45, which is spring-pressed to open position by a spring 46. This valve is provided with an operating arm 47, which is connected by a link 48 to one arm of a bell-crank lever 49 which is fixed on a shaft 50 and has its other arm connected to an operating rod 51. The shaft 50 extends transversely through the passageway 12, and within such passageway has fixed on it a locking arm 52 which when the shaft 50 is turned in a clockwise direction is moved upward into the path of the auxiliary air valve 13 so as to prevent such air valve from opening. Thus by pulling the operating rod 51, the primary air valve 45 is closed and the arm 52 is moved to prevent opening of the auxiliary air valve 13, thus cutting off both the primary and secondary air supplies. This is done during starting, for enriching the mixture. Loosely mounted on the shaft 50 outside the passageway 12 is a second bell-crank lever 53, one arm of which is connected by a link 54 to the downward curved projection 31 from the arm 28, and the other arm of which is provided with a bent finger 55 which is in the path of movement of the

bell-crank lever 49 so as to be engaged thereby during the latter part of the clockwise movement thereof. By reason of this engagement, when the primary air valve 45 is closed and the auxiliary secondary air valve 13 is locked against opening, the latter part 70 of the movement which produces this closing and locking causes the turning of the bell-crank lever 53 in a clockwise direction and through the link 54 causes a similar tilting of the lever 38 and a raising of the 75 needle valve 26, so as to increase the fuel discharged from the fuel nozzle and thus create an enrichment of the mixture both by cutting off the supply of primary and secondary air and increasing the supply of fuel. 80 Thus the fuel valve 26 is opened to admit more fuel either when the throttle valve is opened or when the primary and secondary air supplies are cut off; but the opening of the throttle valve does not affect the primary 85 and secondary air supplies, save as the change in suction may vary automatically the opening of the secondary air valve, and the cutting off of the primary and secondary air supplies does not vary the position of 90 the throttle.

The Venturi tube 20, by reason of this screw-threaded mounting 21 is vertically adjustable, so as to vary the relation between the discharge point of the fuel nozzle 95 22 and the most contracted portion of the Venturi tube, so as to obtain by such adjustment the best action of the fuel discharge and compensate for variations in suction and in number of cylinders in different engines. 100 This vertical adjustment may be obtained by removing either the plug 27 or the auxiliary air valve 13 and its support, thus giving access to the top of the Venturi tube, which is provided with slots 60 for receiving 105 a suitable wrench.

In operation, the engine suction draws in air through the primary air passage 40, which air passes downward along the outside of the Venturi tube 20 with a helical or 110 swirling motion, then turns upward through the Venturi tube with the same swirling motion continued and picks up fuel from the nozzle 22 and any fuel which may have dropped to the bottom of the tube 11, and 115 passes out of the Venturi tube into the horizontal passageway 12, where it is deflected to the right and mixed with the secondary air which is supplied by the automatic secondary air valve 13, the final mixture passing on past the throttle 17 to the engine. As the position of the throttle is changed by manipulating the operating rod 19, the position of the fuel valve is correspondingly changed, as already explained, to vary the 120 fuel supply in accordance with the throttle opening. The relative amounts of throttle and fuel valve openings is determined by 125

adjusting the screw 38. When a rich mixture is desired for starting, the operating rod 51 is pulled to shut off the primary and secondary air supplies and finally to raise 5 the needle valve 26 to increase the supply of fuel therefrom.

One or more overflow pipes 65 are preferably provided at and project slightly above the bottom of the tube 11, so as to allow a 10 small pool of fuel to collect but to limit the size of such pool. By reason of this, the fuel which condenses when the engine is stopped flows back to and collects in the bottom of the tube 11, and when the engine 15 is next started this fuel is picked up by the air and enriches the mixture. The overflow pipe or pipes 65 admit a relatively small amount of air during normal operation, but this air only increases the quantity of primary air.

I claim as my invention:

1. In a carbureter, the combination of an upright Venturi tube, a mixture passage into which said Venturi tube discharges upwardly, said mixture passage having an automatic secondary air valve for admitting secondary air thereinto in accordance with the suction, a fuel nozzle discharging upwardly within said Venturi tube above the 20 lower end thereof, an outer tube surrounding said Venturi tube and provided with a closed lower end from which the lower end of the Venturi tube is upwardly spaced, and a primary air supply passage discharging into said outer tube tangentially around said Venturi tube at a point higher than the lower end of said Venturi tube, so that the air is given a helical or swirling motion around the Venturi tube before entering it 25 and passes under the lower edge of said Venturi tube and upward into the Venturi tube with a continuance of the helical or swirling motion.

2. In a carbureter, the combination of a 30 mixing chamber, a primary air passage leading thereto, a fuel nozzle discharging within said primary air passage, an automatic secondary air inlet valve opening into said mixing chamber, a control valve in the 35 primary air inlet conduit, and means operated by the closing of said control valve for forcing closed the secondary air valve from any open position and positively blocking the opening of said secondary air valve.

3. In a carbureter, the combination of a 40 Venturi tube, a mixture passage into which said Venturi tube discharges, said mixture passage having an automatic secondary air valve for admitting secondary air thereinto in accordance with the suction, a fuel nozzle discharging within and between the ends of 45 said Venturi tube, an outer tube surrounding said Venturi tube and spaced from the inlet end of the latter, and a primary air

supply conduit discharging into said outer tube tangentially around said Venturi tube at a point removed from the inlet end of the latter, so that the air is given a helical or swirling motion around the Venturi tube before entering it and while traveling up 50 through it.

4. In a carbureter, the combination of a 55 Venturi tube, a mixture passage into which said Venturi tube discharges, a fuel nozzle discharging within and between the ends of said Venturi tube, an outer tube surrounding said Venturi tube and spaced from the inlet end of the latter, and a primary air supply conduit discharging into said outer tube tangentially around said Venturi tube 60 at a point removed from the inlet end of the latter, so that the air is given a helical or swirling motion around the Venturi tube before entering it and while traveling up 70 through it.

5. In a carbureter, the combination of a 75 Venturi tube, a mixture passage into which said Venturi tube discharges, a fuel nozzle discharging within and between the ends of said Venturi tube, an outer tube surrounding said Venturi tube and spaced from the inlet end of the latter, and a primary air supply conduit discharging into said outer tube tangentially around said Venturi tube 80 at a point removed from the inlet end of the latter, so that the air is given a helical or swirling motion around the Venturi tube before entering it and while traveling up 85 through it.

6. In a carbureter, the combination of a 90 Venturi tube, a mixture passage into which said Venturi tube discharges, a fuel nozzle discharging within said Venturi tube, an outer tube surrounding said Venturi tube and spaced from the inlet end of the latter, and a primary air supply conduit discharging into said outer tube tangentially around said Venturi tube 95 at a point removed from the inlet end of the latter, so that the air is given a helical motion around the Venturi tube before entering it and while traveling up through it, said primary air conduit where it discharges into said outer tube being inclined obliquely toward the inlet end of the Venturi tube so as to give an initial axial component of motion to the helical stream of air around the Venturi tube.

7. In a carbureter, the combination of a 105 Venturi tube, a mixture passage into which said Venturi tube discharges, a fuel nozzle discharging within said Venturi tube, an outer tube surrounding said Venturi tube and spaced from the inlet end of the latter, 110 and a primary air supply conduit discharging into said outer tube tangentially around said Venturi tube at a point removed from the inlet end of the latter, so that the air is given a helical motion around the Venturi tube before entering it and while traveling up through it, said primary air supply conduit where it discharges into said outer tube having a greater cross sectional dimension transverse to the axis of said outer 115 tube than longitudinally of such axis.

8. In a carbureter, the combination of an 120 upright Venturi tube, a mixture passage into which said Venturi tube discharges upwardly, said mixture passage having an automatic secondary air valve for admitting secondary air thereinto in accordance with the suction, a fuel nozzle discharging up-

- wardly within said Venturi tube above the lower end thereof, an outer tube surrounding said Venturi tube and provided with a closed lower end from which the lower end of the Venturi tube is upwardly spaced, said Venturi tube being hung from its upper end and being axially adjustable vertically to vary the space between the lower end of such Venturi tube and the bottom 10 of said outer tube, and a primary air supply passage discharging into said outer tube tangentially around said Venturi tube at a point higher than the lower end of said Venturi tube, so that the air is given a helical or swirling motion around the Venturi tube before entering it and passes under the lower edge of said Venturi tube and upward into the Venturi tube with a continuance of the helical or swirling motion.

20 8. In a carbureter, the combination of a mixing chamber, a primary air passage leading thereinto, a fuel nozzle discharging within said primary air passage, an automatic secondary air inlet valve opening into 25 said mixing chamber, a control valve in the primary air inlet conduit, and means operated by the closing of said control valve for forcing closed the secondary air valve from any open position and positively blocking 30 the opening of said secondary air valve, said control valve being spring-pressed to open position.

9. In a carbureter, the combination of a mixing chamber, a primary air passage 35 leading thereinto, a fuel nozzle discharging within said primary air passage, an automatic secondary air inlet valve opening into 40 said mixing chamber, a control valve in the primary air inlet conduit, means operated by the closing of said control valve for preventing the opening of said secondary air valve, a needle valve controlling the outlet of said fuel nozzle, and means operated by the latter part only of the closing movement of said control valve for increasing the opening of said needle valve.

45 10. In a carbureter, the combination of a mixing chamber, a primary air passage leading thereinto, a fuel nozzle discharging 50 within said primary air passage, an automatic secondary air inlet valve opening into said mixing chamber, a control valve in the primary air inlet conduit, means operated by the closing of said control valve for preventing the opening of said secondary air valve, said control valve being spring-pressed to open position, a needle valve controlling the outlet of said fuel nozzle, and means operated by the latter part only of the closing movement of said control valve for increasing the opening of said needle valve.

55 11. In a carbureter, the combination of a mixing chamber, a primary air passage leading thereinto, a fuel nozzle discharging 60 within said primary air passage, an automatic secondary air inlet valve opening into said mixing chamber, a control valve in the primary air inlet conduit, means operated by the closing of said control valve for preventing the opening of said secondary air valve, so that the air is given a helical or swirling motion around the Venturi tube before entering it and passes under the lower edge of said Venturi tube and upward into the Venturi tube with a continuance of the helical or swirling motion.

65 12. In a carbureter, the combination of a mixing chamber, a primary air passage leading thereinto, a fuel nozzle discharging within said primary air passage, an automatic secondary air inlet valve opening into 70 said mixing chamber, a control valve in the primary air inlet conduit, means operated by the closing of said control valve for preventing the opening of said secondary air valve, a needle valve controlling the outlet of said fuel nozzle, and means operated by the closing movement of said control valve for increasing the opening of said needle valve.

75 13. In a carbureter, the combination of an upright Venturi tube, a mixture passage into which said Venturi tube discharges upwardly, a fuel nozzle discharging upwardly 80 within said Venturi tube above the lower end thereof, an outer tube surrounding said Venturi tube and provided with a closed lower end from which the lower end of the Venturi tube is upwardly spaced, and a primary air supply passage discharging 85 tangentially around said Venturi tube at a point higher than the lower end of said Venturi tube, so that the air is given a helical or swirling motion around the Venturi tube before entering it and passes under the lower edge of said Venturi tube and upward into the Venturi tube with a continuance of the helical or swirling motion.

90 14. In a carbureter, the combination of an upright Venturi tube, a mixture passage into which said Venturi tube discharges upwardly, a fuel nozzle discharging upwardly 95 within said Venturi tube above the lower end thereof, an outer tube surrounding said Venturi tube and provided with a closed lower end from which the lower end of the Venturi tube is upwardly spaced, said Venturi tube being hung from its upper end and being axially adjustable vertically to 100 vary the space between the lower end of such Venturi tube and the bottom of said outer tube, and a primary air supply passage discharging into said outer tube tangentially around said Venturi tube at a point higher than the lower end of said Venturi tube, so that the air is given a helical or swirling motion around the Venturi tube before entering it and passes under the lower edge of said Venturi tube and upward into the Venturi tube with a continuance of the helical or swirling motion.

105 15. In a carbureter, the combination of an upright Venturi tube, a mixture passage into which said Venturi tube discharges upwardly, a fuel nozzle discharging upwardly 110 within said Venturi tube above the lower end thereof, an outer tube surrounding said Venturi tube and provided with a closed lower end from which the lower end of the Venturi tube is upwardly spaced, said Venturi tube being hung from its upper end and being axially adjustable vertically to 115 vary the space between the lower end of such Venturi tube and the bottom of said outer tube, and a primary air supply passage discharging into said outer tube tangentially around said Venturi tube at a point higher than the lower end of said Venturi tube, so that the air is given a helical or swirling motion around the Venturi tube before entering it and passes under the lower edge of said Venturi tube and upward into the Venturi tube with a continuance of the helical or swirling motion.

120 16. In a carbureter, the combination of an upright Venturi tube, a mixture passage into which said Venturi tube discharges upwardly, a fuel nozzle discharging upwardly 125 within said Venturi tube above the lower end thereof, an outer tube surrounding said Venturi tube and provided with a closed lower end from which the lower end of the Venturi tube is upwardly spaced, said Venturi tube being hung from its upper end and being axially adjustable vertically to 130 vary the space between the lower end of such Venturi tube and the bottom of said outer tube, and a primary air supply passage discharging into said outer tube tangentially around said Venturi tube at a point higher than the lower end of said Venturi tube, so that the air is given a helical or swirling motion around the Venturi tube before entering it and passes under the lower edge of said Venturi tube and upward into the Venturi tube with a continuance of the helical or swirling motion.

edge of said Venturi tube and upward into the Venturi tube with a continuance of the helical or swirling motion.

15. In a carbureter, the combination of a mixing chamber, a fuel nozzle discharging fuel thereinto, a needle valve controlling the supply of fuel from said fuel nozzle, said mixing chamber being provided with an air inlet opening, a throttle controlling the discharge of the mixture from said mixing chamber, manually operated means for cutting off the supply of air to said air inlet opening, and means for opening said needle valve to increase the supply of fuel independently by the opening of the throttle and by the operation of said manually operated means.

16. In a carbureter, the combination of an upright Venturi tube, a mixture passage into which said Venturi tube discharges upwardly, said mixture passage having an automatic secondary air valve for admitting secondary air thereinto in accordance with the suction, a fuel nozzle discharging upwardly within said Venturi tube above the lower end thereof, an outer tube surrounding said Venturi tube and provided with a closed lower end from which the lower end of the Venturi tube is upwardly spaced, and a primary air supply passage discharging into said outer tube tangentially around said Venturi tube at a point higher than the lower end of said Venturi tube, so that the air is given a helical or swirling motion around the Venturi tube before entering it and passes under the lower edge of said Venturi tube and upward into the Venturi tube with a continuance of the helical or swirling motion, said outer tube having an open overflow pipe opening into it slightly above its bottom but below the lower end of said Venturi tube.

17. In a carbureter, the combination of a mixing chamber having openings for the admission of primary and secondary air, a fuel nozzle for supplying fuel to the primary air admitted to the mixture chamber, a needle valve controlling the outlet from said fuel nozzle, valve means for shutting off the supply of primary and secondary air to said mixture chamber, and means operated by the shutting off of both said primary and secondary air for causing the opening of said needle valve.

18. In a carbureter, the combination of a mixing chamber having openings for the admission of primary and secondary air, a fuel nozzle for supplying fuel to the primary air admitted to the mixture chamber, a needle valve controlling the outlet from said fuel nozzle, a valve controlling the supply of primary air, means operated by the closing of said primary air valve for producing an opening in said needle valve, a throttle for controlling the outlet of the mixture from

said mixture chamber, and means operated by the opening of said throttle for opening said needle valve.

19. In a carbureter, the combination of a mixing chamber having openings for the admission of primary and secondary air, a fuel nozzle for supplying fuel to the primary air admitted to the mixture chamber, a needle valve controlling the outlet from said fuel nozzle, an automatic air valve controlling the admission of secondary air to said mixture chamber, means for preventing said automatic secondary air valve from opening, means operated by the operation of said opening-preventing means for producing an opening of said needle valve, a throttle for controlling the outlet of the mixture from said mixture chamber, and means operated by the opening of said throttle for opening said needle valve.

20. In a carbureter, the combination of a mixing chamber having openings for the admission of primary and secondary air, a fuel nozzle for supplying fuel to the primary air admitted to the mixture chamber, a needle valve controlling the outlet from said fuel nozzle, valve means for shutting off the supply of primary and secondary air to said mixture chamber, means operated by the shutting off of both said primary and secondary air to cause the opening of said needle valve, a throttle for controlling the outlet of the mixture from said mixture chamber, and means operated by the opening of said throttle for opening said needle valve.

21. In a carbureter, the combination of an upright Venturi tube, a mixture passage into which said Venturi tube discharges upwardly, a fuel nozzle discharging upwardly within and between the ends of said Venturi tube, an outer tube surrounding said Venturi tube and spaced from the lower end of the latter and having an inlet opening for primary air at a point above from the lower end of said Venturi tube, said outer tube having a closed lower end below the lower end of said Venturi tube, and said parts being provided with means for giving the air a helical motion around the Venturi tube before entering it.

22. In a carbureter, the combination of an upright Venturi tube, a mixture passage into which said Venturi tube discharges upwardly, a fuel nozzle discharging upwardly within said Venturi tube above the lower end thereof, an outer tube surrounding said Venturi tube and provided with a closed lower end from which the lower end of the Venturi tube is upwardly spaced, and a primary air supply passage discharging into said outer tube tangentially around said Venturi tube at a point higher than the lower end of said Venturi tube, so that the air is given a helical or swirling motion

around the Venturi tube before entering it and passes under the lower edge of said Venturi tube and upward into the Venturi tube with a continuance of the helical or swirling motion, said outer tube having an open overflow pipe opening into it slightly above its bottom but below the lower end of said Venturi tube.

In witness whereof, I have hereunto set my hand at Indianapolis, Indiana, this 17th ¹⁰ day of January, A. D. one thousand nine hundred and sixteen.
